(57) **CLAIM**

The ornamental design for a grill tool, as shown and described.

DESCRIPTION

FIG. 1 is a front, left, perspective view of a grill tool showing our new design;

FIG. 2 is a front, left, perspective view of the grill tool of FIG. 1 in a first open position;

FIG. 3 is a front, left, perspective view of the grill tool of FIG. 1 in a second open position;

FIG. 4 is a front view of the grill tool of FIG. 1;

FIG. 5 is a back view of the grill tool of FIG. 1;

FIG. 6 is a left side view of the grill tool of FIG. 1, the right side view being a mirror image of the left side view;

FIG. 7 is a top view of the grill tool of FIG. 1; and,

FIG. 8 is a bottom view of the grill tool of FIG. 1.

The broken line showing in all figures is for illustrative purposes only and forms no part of the claimed design.
